et al.

UNITED STATES PATENT OFFICE

RICHARD M. DUGDALE, OF DEDHAM, MASSACHUSETTS, ASSIGNEE TO FARRINGTON MANUFACTURING COMPANY, OF BOSTON, MASSACHUSETTS, A CORPORATION OF MASSACHUSETTS

STAMPING DEVICE

Application filed July 26, 1930. Serial No. 470,898.

This invention relates to printing or stamping devices which may for example be of the type illustrated and described in my copending application Serial No. 391,788 filed September 11, 1929, and Serial Nos. 404,290 and 404,291 both filed November 2, 1929. Devices of this type are useful in printing from detachable sheet metal printing plates of the type used to identify customers in retail transactions, and the devices include as an operative element an ink ribbon which is pressed, together with a sheet to be printed, against the sheet metal printing plate to effect printing. Objects of the invention are to provide for advancing the ribbon to present fresh portions thereof to the printing pressure device without danger of breaking the ribbon and without danger of smearing the printed sheet.

The present invention is particularly useful in devices such as described in the above copending applications wherein mechanism for advancing the ribbon is operated by movement of the mechanism which causes the printing pressure to be applied to the ribbon. In this connection my invention provides a simple compact device wherein actuation of the pressure member and of the ribbon advancing mechanism is determined by movement of a single operating handle and yet wherein the above described difficulties of breakage or smearing are obviated. Other advantages and structural improvements will be apparent from the explanation in this specification and the accompanying drawings of a specific and illustrative embodiment of my invention.

For the purposes of illustration and by way of example my invention will be explained with reference to one specific embodiment wherein it is utilized in a device of the type claimed in my copending applications referred to above.

In the drawings:

Fig. 1 is a side elevation of a stamping or printing device, the view being taken from the side of the device opposite to that at which the operator usually stands, and a portion of the side wall of the device being broken away;

Fig. 2 is a fragmentary view similar to Fig. 1, showing certain parts of the device in operation;

Fig. 3 is a section on the line 3—3 of Fig. 2;

Fig. 4 is a section on the line 4—4 of Fig. 1 with the ribbon reels and certain other parts removed; and

Fig. 5 is a fragmentary side elevation of a portion of the device, this view being taken in a direction opposite to that of Fig. 1.

The illustrated embodiment of my invention includes numerous parts similar to or identical with corresponding parts in the device illustrated and claimed in my copending application Serial No. 404,291 filed November 2, 1929, which may be referred to for a fuller description of these parts. The illustrated device, which is adapted particularly for printing customers' names and addresses upon sales slips in connection with retail transactions, includes a base 11, a plate holder, indicated generally by the reference character 12, rigid with the base and spaced therefrom by a block 13, a casing 14 hinged to the plate holder and base at 15 and containing pressure-applying mechanism and ribbon-feeding and reversing mechanism, and an operating handle 16 for swinging the casing and contained mechanism toward and from the plate holder 12 and for operating the pressure applying mechanism and ribbon feeding and reversing mechanism. A suitable printing plate 18, which is preferably of the type illustrated and claimed in my copending application Serial No. 374,715 filed June 29, 1929, comprising a sheet of ductile metal having a struck-up central portion which carries type characters 19, (Fig. 2) may be detachably retained by the plate holder 12. The type characters 19 of this plate are preferably raised characters disposed in direct order so that a sheet of paper to be printed may be laid directly upon the printing plate and receive printed indicia upon its upper face as a result of the printing operation. An ink ribbon 29 is contained within the casing 14 and overlies a sheet of paper thus placed upon the printing plate.

A suitable pressure applying member, 100

which may be any kind of a platen, but which is herein shown as a pressure roller 28 having hub members 39 movably retained within slots 40 of a channel shaped guide member 43, 5 adapted to be moved across a printing plate retained by the holder and in so doing to press the inked ribbon 29 and one or more sheets of paper against the plate. Suitable mechanism for moving the pressure roller 28 10 preferably comprises a vertical plunger 30 connected by a pin and slot connection to the operating handle 16 and movable downwardly against the action of a coil spring 31. The plunger 30 carries a cam surface 32 at its 15 lower end which operatively engages a cam follower 33 (Fig. 5) mounted upon a bifurcated bracket 36 which is pivotally mounted at 36a to a sleeve 81 fast to the casing 14. The bifurcated bracket 36 engages 20 at its lower end opposite ends of the pressure roller 28. In this manner pressing down on the operating handle 16 depresses the plunger 30 and causes the cam surface 32 to swing the cam follower 33 and the bracket 25 36 to the right in Fig. 1, thus carrying the pressure roller 28 to the right across the printing plate. Releasing the operating handle 16 enables the spring 31 to raise the plunger 30 to its initial position, while a coil spring 30 35 serves to return the bifurcated bracket 36 and the pressure roll 28 to their positions at the left-hand side of the casing in Fig. 1. It will readily be understood that the exact structure of the parts thus far described is 40 not essential to my invention, as numerous other pressure-applying devices and operating mechanisms therefor might be employed to press an inked ribbon against a sheet of paper and against the printing plate 18. At 45 this point it should be noted however that the pressure-applying mechanism is preferably capable of applying a considerable pressure to the inked ribbon 29 and the sheet or sheets of paper being printed, in order to obtain clear, legible impressions, preferably on a number of superposed sheets with interposed carbon sheets.

The device preferably includes in addition to the outer casing 14, an inner casing 44 50 which may be fastened to the wall of the outer casing (Fig. 4) and which preferably comprises spaced vertical side portions 42 to which the channel-shaped guide 43 is preferably fastened.

The inked ribbon 29 is wound upon ribbon 55 reels 40 and 41 rotatably mounted upon shafts 52 and 53 which are retained in the casing 14 by means of screws 62, (Fig. 4) and which have enlargements in the form of flanges 63 60 spaced from the back of the outer casing 14 adapted loosely to receive a ratchet wheel 50 or 51 and a spacing washer 64. Each ratchet wheel has pins 65 projecting forwardly therefrom immediately outside the periphery of 65 the flange 63 of the shafts 52 and 53 and

adapted operatively to engage struck-up ears 66 on the ribbon reel, thus to rotate the reel. As shown in Figs. 1 and 4, a spring 70 is mounted on the inner casing 44 beneath each ribbon reel by means of struck-up ears 67 70 and bears against the spacing washer 64. This arrangement of parts is such that either of the reels 40 or 41 may be rotated by force applied to the ratchet teeth of the associated ratchet, but is such that rotation of either of 75 the wheels is resisted by the frictional engagement of the spring 70 with the spacing washer 64. As shown in Fig. 1 the ratchet wheels have their teeth reversed with respect to each other so that the ink ribbon 29 is 80 wound in one direction when one of the ratchet wheels is rotated and in the opposite direction when the opposite ratchet wheel is rotated.

The device is preferably provided with 85 mechanism for winding up the ribbon upon one of these reels upon movement of the actuating plunger 30. Referring to Fig. 1, a tumbler 46 is pivotally mounted on the lower end of the plunger 30 between the two ribbon 90 reels to swing toward either of these reels. Tumbler 46 is provided on one face with a pair of countersunk holes 47 and 48 on opposite sides of its center, and plunger 30 carries a spring-pressed pin 49 adapted to project 95 into either of these holes and thereby yielding to position the tumbler adjacent to one or the other of these rolls of inked ribbon. In the position of Fig. 1, pin 49 is shown as 100 engaging hole 47. Tumbler 46 is provided with two pivotally mounted pawls 58 and 59 for engaging respectively ratchet wheels 50 and 51. As the tumbler 46 returns to its uppermost position at the end of the printing operation, one of the pawls 58 or 59, depending upon the position of the tumbler, engages 105 the adjacent ratchet wheel and winds a portion of the ribbon upon the corresponding reel. In this manner the ribbon is advanced in a step by step manner while the ratchet 110 wheels are prevented from moving unduly by means of the frictional engagement of the springs 70 with the spacing washers 64. The tumbler 46 is preferably provided at its opposite sides, adjacent the respective rolls of ribbon, with ribbon-contacting members 55 and 56. As the amount of ribbon on a reel increases to a certain extent the ribbon wound on the reel will force this ribbon-contacting member away from the axis of the reel, thus 115 swinging the tumbler 46 to its opposite position and effecting a reversal of feeding direction of the ribbon.

From the above description of a preferable form of pressure-applying mechanism and a 120 preferable form of ribbon-feeding mechanism, it will appear that with these mechanisms thus operating in conjunction there is, unless some precautionary measures are observed, danger that the device will be so op- 125 130

erated that the ribbon-feeding mechanism might either break the ribbon while the latter is subjected to the compression of the pressure roll, or else advance the ribbon while the latter is being pressed against the printed sheet and thereby produce a smear upon the upper surface of the sheet.

For the purpose of protecting the device against such undesired operations, provision is made for regulating the tension of the portion of ribbon intermediate the winding reel and the pressure roll, the regulation of tension preferably being obtained by a controlled shortening of the path of ribbon between these two instrumentalities so that winding may take place without simultaneous movement of the ribbon under the pressure roll. As illustrative of preferred means for accomplishing this end, the accompanying drawings show a pair of springs 80, having cut-out portions 80^a (Fig. 3) to increase their resiliency, and fastened to opposite ends of the channel-shaped guide 43. These springs 80 extend generally in prolongation of the side portions 42 of the inner casing and constitute flexible or yielding guide members for the ribbon intermediate the ribbon reels and the fixed guides comprising the side portions 42 of the inner casing. Referring to Fig. 1, the inked ribbon 29 passes from one ribbon reel to the other in an indirect path, portions of which are determined by the flexible or yielding guide members 80 which are so disposed that they define projecting angles of the ribbon path. Preferably the springs are rounded at their outer ends, as shown in Figs. 1 and 2, to facilitate the passage of the ribbon. The arrangement of these springs 80 at projecting angles of the path of the ribbon is such that undue tension upon the ribbon as set up by simultaneous winding of a ribbon reel and compression of a ribbon by the pressure roll, causes the adjacent spring 80 to yield and thereby shorten to some extent the path of the ribbon and relieve the tension thereof, thus preventing breaking or preventing the ribbon 29 from being pulled from under the pressure roll with a consequent smearing of the printed sheet. Fig. 2 illustrates diagrammatically this mode of operation, and referring to this figure it will be noted that the pressure roll moving (on its return stroke) in the direction of the arrow M, has not yet left the region of the raised type characters 19 of the printing plate but is still compressing the inked ribbon therebetween. At this stage the tumbler 46, through its pawl 58, has already engaged the ratchet wheel of the reel 40 and has wound a certain amount of ribbon thereon, the increased tension thus set up in the ribbon having caused the adjacent spring 80 to move slightly in a direction which tends to shorten the path of the ribbon.

Further movement of the pressure roll 28 in the direction of the arrow M in Fig. 2 so that

the roll leaves the region of the raised type characters 19 and thus ceases to press hard upon the inked ribbon 29, will relieve the excess tension in the ribbon, thereby enabling the flexed spring 80 to return to its initial vertical position of Fig. 1. This outward motion of the spring 80, which preferably takes place while the ratchet wheel is still engaged by the pawl of the tumbler, operates to draw ribbon from the reel 41 past the guide 42 and under the roll 28. Such movement of the ribbon under the influence of the spring 80 is unaccompanied by any danger of breakage or smearing since the roll 28 has at this point ceased to apply pressure to the ribbon. The spring 80 in addition to serving as a tension regulating member may therefore also be regarded as a device effective to receive energy from the initial actuation of the associated ratchet wheel, and effective later to advance the ribbon underneath the pressure roll when the pressure applied by the pressure roll has diminished to such an extent that danger of breakage of the ribbon or smearing of the sheet is passed.

I claim:

1. A stamping device comprising a plate holder for detachably retaining a printing plate, an ink ribbon adapted to overlie a sheet of paper when the latter is placed in printing position upon a printing plate retained by the plate holder, a pressure roll movable over the portion of the ink ribbon which overlies the printing plate, operating mechanism for thus moving the roll, rotatable ribbon reels adapted to wind up and unwind the ribbon, reel-rotating mechanism operable by said operating mechanism to rotate one of said reels during movement of the pressure roll, and a yieldable member defining a portion of the path of said ribbon, said member, through yielding, permitting an end portion of the ribbon to be wound up without simultaneous advance of the portion of ribbon engaged by the pressure roll, subsequent return of the yieldable member serving to advance the remainder of the ribbon.

2. A stamping device comprising a casing, an ink ribbon and rotatable reels therefor within the casing, a pressure roll adapted to press the ribbon toward a printing plate, a guide for the roll extending across the casing, guides defining generally vertical paths for the ribbon leading to and from a horizontal plane traversed by the roll, and spring abutments defining projecting angles in the path of the ribbon adjacent the reels, whereby upon tensioning of the ribbon by rotation of a reel the adjacent abutment yields to permit straightening and winding up of a portion of the ribbon without corresponding simultaneous progression of the portion of the ribbon engaged by the roll.

3. In a stamping device, a horizontal guide

for a pressure roll, a vertical ribbon guide at each end of the horizontal guide for guiding an ink ribbon to a horizontal plane adjacent the bottom of the horizontal guide, and approximately vertically disposed springs at each end of the horizontal guide defining paths for the ribbon as the latter approaches and leaves the vertical ribbon guides.

Signed by me at Boston, Massachusetts,
10 this 15th day of July, 1930.
